BY ATTY: *Edward M. Kojima*

UNITED STATES PATENT OFFICE.

SACHIKO UMEZAWA, OF CALEXICO, CALIFORNIA.

FABRIC-CRIMPING DEVICE.

Application filed October 1, 1923. Serial No. 666,024.

To all whom it may concern:

Be it known that I, SACHIKO UMEZAWA, a subject of the Emperor of Japan, residing at Calexico, in the county of Imperial 5 and State of California, have invented a new and useful Fabric-Crimping Device, of which the following is a specification.

The present invention relates to a fabric-crimping device, and has for its object, to 10 provide a simple and efficient arrangement of elements for crimping cloth fabrics and paper to render the same capable of simulating the foliage and petals of flowers, and to provide material for ornamentation.

15 With these objects in view, the invention consists in the combination and arrangement of parts as hereinafter more fully described and set forth in the appended claims.

In the drawings, Figure 1 is a top plan 20 view of the device. Fig. 2 is a longitudinal and sectional view of the same. Fig. 3 is a detail view of the cord retaining element. Fig. 4 is a detail view of the cord wrapping element. Fig. 5 is a plan and detail view 25 of the creasing fork. Fig. 6 is a perspective view of the device showing the method of using the creasing fork to form the longitudinal creases in the fabric. Fig. 7 is a perspective view of the device showing the 30 method of using the creasing fork and wrapping cords to form the lateral creases in the fabric. Fig. 8 is a view showing the flower which may be made from the crimped fabric. Fig. 9 is a transverse section of the device 35 showing the apertures arranged for changing the position of the partition members to vary the width of the slots in the device.

My improved device for making artificial 40 petals from cloth fabric, and for making fabric decorative elements, consists of a tubular member 11, having longitudinal 45 slots 12, 13 and 14, and on the opposite side, a longitudinal slot 15, adapted to receive the cord retaining member 16. The end 17, of member 11, is provided with a detachable cover 18.

The cord-wrapping member 19, which has 50 a cylindrical form, is provided with transverse apertures 20, through which pass the wrapping cords 21. The cords 21 each have one end connected to the cord-retaining member 16. A creasing fork 22 is used to force the fabric 23 into the crimping slots 12, 13 and 14. The partition members 24 55 and 25 are detachable, each being provided with an integral projecting pin 26, at each

end, engaging with corresponding holes in the body 11 and in the cover 18. These partition members may be removed, or may be so placed in position as to form but two 60 crimping slots. The holes 27 determine the adjoining positions of the partition members to form the two crimping slots.

In use, the cloth fabric, preferably silk, is dampened, and, while still moist, is 65 wrapped around the body member 11. Suitable colors are then applied to the cloth fabric, which, when the material is finally assembled into a flower, will simulate the coloring and shading of the flower petals. 70 While the fabric is moist, the coloring material will spread easily. The creasing fork 22 is then used to form the longitudinal creases in the fabric, as shown in Fig. 6. The cords 21 are then wrapped around the 75 mandrel body 11 and over the cloth fabric. The member 19, serves to maintain the cords in spaced relation while being wound in spiral arrangement. The ends of the cloth fabric are then forced toward each other, 80 until the strands of the wrapping cord are adjoining one another, as shown in Fig. 7. This produces the lateral creases in the cloth fabric. The device is then set aside until the fabric is dry. Then the cords are unwound, 85 and the fabric is unrolled from the mandrel body. Each piece of crimped cloth fabric is then folded and assembled to form a flower petal, and, when assembled as shown in Fig. 8, is well adapted to simulate the petal of a 90 flower.

To vary the width of the crimp, the partition members 24 and 25 may be positioned in the center to form two crimping slots. The cover 18, maintains the members 24 and 95 25 in position, and is frictionally retained upon the end of mandrel 11.

From the foregoing description and drawings it may be seen that I have produced a simple and efficient apparatus for producing 100 artificial petals from a cloth fabric.

What is claimed is:

1. The combination with a tubular member having a series of longitudinal crimping slots, and a longitudinal slot disposed in 105 opposite relation to the crimping slots, of a cord retaining member slidable in said slot, a series of wrapping cords connected at one end to the cord retaining member, a spacing member through which the wrapping cords 110 pass, and a creasing fork adapted to force the fabric into the crimping slots.

2. In a fabric crimping device, the combination with a tubular member having a series of longitudinal crimping slots and a longitudinal slot in opposed relation to the crimping slots, a cord retaining member sliding in said slot, and cord spacing member, and wrapping cords extending from the cord retaining member and passing through the spacing member, of a creasing fork adapted to press the fabric into the longitudinal slots, and a cover for the end of the tubular member and detachable for varying the width of the longitudinal crimping slots.
5. In a fabric crimping device, the combination with a tubular member having a series of longitudinal crimping slots and a longitudinal slot in opposed relation to the crimping slots, a cord retaining member 10 slidable in said slot, wrapping cords extending from the retaining member, and a spacing member in engagement with the cords for wrapping the cords spirally around the tubular member, of a crimping fork to press the cloth fabric into the longitudinal crimping grooves.
15. In a fabric crimping device, the combination with a tubular member having a series of longitudinal creasing slots, and adapted to receive a dampened cloth fabric, of cords adapted to be wrapped spirally around the tubular member and over the cloth fabric, and a creasing fork adapted to form longitudinal depressions in the cloth fabric and in engagement with the crimping slots.
20. In a fabric crimping device, the combination with a tubular member having a series of longitudinal creasing slots, and adapted to receive a dampened cloth fabric, of a creasing fork co-operative with the longitudinal slots to crease the fabric longitudinally, cords adapted to be wrapped spirally around the tubular member and over the cloth, a spacing member to space apart the cords, and a detachable cover for the end of the tubular member for varying the width of the creasing slots.
25. In a fabric crimping device, a longitudinally slotted mandrel to receive the fabric, a fork to force the fabric into the longitudinal slots, a plurality of flexible cords, means for wrapping the cords spirally around the mandrel and over the fabric, said fork being adapted for forcing the spiral strands together, and a detachable end for the mandrel for spacing the width of the slots.
30. In a fabric crimping device, a longitudinally slotted mandrel to receive a dampened cloth fabric, a fork cooperative with the longitudinal slots to crease the fabric longitudinally, flexible cords connected at one end with the mandrel, means for spacing the cords spirally around the mandrel and over the cloth fabric, said fork forcing the spiral strands of the cords together to crease the fabric laterally, and a detachable end for the mandrel.
35. In a fabric crimping device, a tubular form having longitudinal slots and adapted to receive a dampened fabric, a detachable partition element between two contiguous slots, a separate fork member cooperating with the slots to form longitudinal creases in the fabric and to form lateral creases in the fabric subsequently, and a detachable end for the tubular form.
40. In testimony whereof, I hereunto affix my signature.

SACHIKO UMEZAWA.
